TOY TRACKWAY SYSTEM

Alfred Einfalt, Nurnberg, Germany, assignor to Gebruder Einfalt Blechspielwarenfabrik, Nurnberg, Germany, a firm

Filed Feb. 28, 1961, Ser. No. 92,192

Claims priority, application Germany, Mar. 2, 1960
8 Claims. (Cl. 104—60)

The invention relates to a toy comprising a runway composed of a plurality of track sections running one into the other at one or more points and having several toy vehicles movable thereon.

The object of the invention is to produce a toy which is characterized by astonishing, unexpected effects. Moreover, the toy according to the invention constitutes an interesting subject of occupation for children with continually recurring surprising ideas. The attraction for children is therefore very considerable.

To attain this object, the toy according to the invention is constructed in such a manner that tracks arranged on and forming the runway are interconnected by two branch tracks and in addition lead into two inner connecting tracks which are at a different level to the branch tracks, control means being provided for stopping the vehicles and branch guides for guiding the vehicles are actuated by the vehicles themselves.

At the same time it is particularly advantageous to construct the branch tracks as two arcuate curves which are arranged in the form of a hyperbola on the runway between the two outer track sections because then the toy vehicles on the runway can always run only in one direction. The inner tracks are conducted over the branch tracks by means of a bridge. The runway therefore has no crossings.

The attraction of the toy is further enhanced by providing stopping means on the outer track sections between the branch tracks. The stopping members thereof always bring the approaching vehicle to a standstill. It can only continue its travel after the stopping means in question has been disengaged or rendered ineffective. The disengagement of the stopping means is effected by means of a control element projecting into the runway at another point thereof. The control members for the stopping means on the outer track sections are preferably located near the inner tracks remote from the stopping points. This produces an unexpected effect in that the vehicle brought to a standstill at a stopping point is again set in motion without any apparent reason. The stopping of a vehicle is effected by a drop-plate on the vehicle which falls into a slot in the track. The lifting or disengagement of the drop-plate is effected by a plate which is mounted on a pivot lever and can be pressed up to move the drop-plate out of the slot. To effect this, the control member in question is mounted on the end of another lever which is itself mounted on the underside of the runway. Its centre of gravity is located between the stopping point and its bearing point, so that when at rest, the control member is always in operative position at the stopping point.

In order to prevent a stopped vehicle from being run into by a following vehicle, it is also proposed, according to the invention, to control a switch plate from the stopping point which switches the following vehicle on to a branch track if the stopping point is occupied.

For this purpose a two-armed lever is preferably used, one arm of which is depressed by the stopped vehicle so that its other arm swings the switch plate into the track. The centre of gravity of the two-armed lever is located between its bearing point and the switch plate so that, when at rest, the run-in to the outer track is always open.

Other features and advantages will become apparent

2

from the following description of the accompanying drawings in which an embodiment of the invention is illustrated diagrammatically by way of example.

FIG. 1 shows the runway in top plan view;

FIG. 2 is a section on line II—II of FIG. 1;

FIG. 3 is a section taken in the plane III—III of FIG. 1;

FIG. 4 is a section similar to that shown in FIG. 3;

FIG. 5 a section taken on line V—V of FIG. 1, and

FIG. 6 is a view similar to that shown in FIG. 5, while FIG. 7 shows a toy vehicle in elevation, partly broken away, and

FIG. 8 a bottom plan view of a toy vehicle with the bottom plate partly removed.

As can be seen from FIG. 1, two track sections b_1 and b_2 are arranged at the outer edges of a plate a carrying the runway. The track b_1 leads into an inner track d_1 over curved track sections c_1 and c_2 . The track b_2 leads into a connecting inner track d_2 over curved track sections c_3 and c_4 . Furthermore, the outer tracks b_1 and b_2 are connected by means of the branch track sections e_1 and e_2 . These tracks are arranged in such a manner on the plate a that at the transition point between outer track and curved track they always lead into or out from the latter.

The inner connecting track sections d_1 and d_2 are conducted over the branch track sections e_1 and e_2 by means of a bridge f . The run-in and run-out to and from the bridge are formed by ramps g_1 and g_2 which are produced by bulging the plate a upwards. Stopping means i_1 and i_2 are provided in the sections h_1 and h_2 of the outer sections b_1 and b_2 . These stopping means are formed by slots k_1 and k_2 in the plate a into which slots a drop-plate l on the vehicles m drops when a vehicle runs over a slot.

The drop-plates l stop the driving mechanism of the vehicle by their teeth n engaging in a pinion o , and in addition an abutment p on the drop-plate l brings the vehicle to a standstill at the point provided for the purpose.

To prevent a vehicle thus stopped from being run into by a following vehicle, a control member q_1 or q_2 is provided at each of the stopping points i_1 or i_2 , which member is actuated by the vehicle brought to a standstill at a stopping point and effects the shifting of a switch plate r_1 or r_2 connected to it. These switch plates deflect a following vehicle on to a branch track e_1 or e_2 . Consequently a collision of two vehicles on the runway is reliably prevented. The control members q_1 and q_2 each preferably consist of a two-armed lever s_1 or s_2 with a switch plate r_1 or r_2 mounted on the underside of the plate. The centre of gravity of each of these levers is located between its switch plate and its bearing point (see FIGS. 5 and 6).

The release of a vehicle brought to a standstill at one of the stopping points i_1 or i_2 is effected by control members t_1 or t_2 which control members are actuated by a vehicle running over them. It is also advantageous in this connection for the control member t_1 to be controlled from the inner track d_2 and the control member t_2 from the inner track d_1 . The connection of the control members t_1 , t_2 with their respective control plates u_1 , u_2 is effected by pivot levers v_1 and v_2 respectively, which levers are located on the underside of the plates u_1 , u_2 and their bearing points (FIGS. 3 and 4).

I claim:

1. A toy composed of a runway for accommodating a plurality of vehicles running thereon, said runway comprising two outer track sections arranged in spaced parallel relation, two separate branch track sections interconnecting said outer track sections at spaced branching points on each outer track, two inner track sections arranged in parallel relation between said outer track sections, and two pairs of curved track sections each pair

forming extensions of the two ends of one of said outer track sections leading to the adjacent ends of one of said inner track sections, said inner track sections and said branch track sections being mounted to cross each other at different levels and including switch plates provided at two of said branching points for switching vehicles on to a branch line, and switch control means operated by a vehicle brought to a standstill at a stopping point in an outer track section for controlling the position of said switch plates to divert an oncoming vehicle so as to avoid a collision.

2. A toy according to claim 1, wherein said switch control means comprises a two-armed lever, one arm of which is depressed by a vehicle at a stopping point, the other arm of which being thereby raised and actuates a switch plate which deflects on to a branch track a vehicle running on an outer track section.

3. A toy according to claim 2, wherein the center of gravity of the two-armed lever is located between its bearing point on the runway and its switch plate.

4. A toy composed of a runway for accommodating a plurality of vehicles running thereon in one direction and consisting of a plurality of interconnecting tracks, said runway comprising two outer track sections arranged in spaced parallel relation, two separate branch track sections interconnecting said outer track sections at spaced branching points on each outer track, two inner track sections arranged in parallel relation between said outer track sections, and two pairs of curved track sections each pair forming extensions of the two ends of one of said outer track sections leading to the adjacent ends of one of said inner track sections, said inner track sections and said branch track sections being mounted to cross

each other at different levels, track switching members at certain of said branching points to effect changes in the vehicle track, vehicle-stopping means located at stopping points in said track sections, vehicle-actuated members located at said stopping points for effecting operation of certain ones of said track switching members.

5. A toy according to claim 4 wherein said vehicle stopping means are located at stopping points in the outer track sections between the branching points of said branch sections.

6. A toy according to claim 5 wherein additional vehicle-operated control members are provided on the connecting inner track sections and operating to release the stopping means at said stopping points.

7. Toy according to claim 6, wherein the additional control members for the stopping points are each arranged on the inner track section remote from the outer track section in which the particular stopping point is located.

8. A toy according to claim 6, wherein each of said additional control members comprises a two-armed pivot lever mounted on the underside of the runway in such a manner that its center of gravity is located between its pivot axis and the stopping point.
